United States Patent Office

Des. 212,438
Patented Oct. 15, 1968

212,438

GARDEN TRAY

Mary Fujita, 74 White St.,
Watsonville, Calif. 95076

Filed Apr. 8, 1968, Ser. No. 11,364

Term of patent 14 years

(Cl. D35—3)

FIG. 1.

FIG. 2.

FIGURE 1 is a first perspective view showing a garden tray in accordance with my new design; and

I claim:

The ornamental design for garden tray, substantially as shown.
